UNITED STATES PATENT OFFICE.

JOSEPH C. WHITE, OF CHELSEA, MASSACHUSETTS.

COMBINED PISTOL AND KNIFE.

SPECIFICATION forming part of Letters Patent No. 626,472, dated June 6, 1898.

Application filed March 28, 1898. Serial No. 675,250. (No model.)

To all whom it may concern:

Be it known that I, JOSEPH C. WHITE, of Chelsea, in the county of Suffolk and State of Massachusetts, have invented an Improved 5 Combined Pistol and Knife, of which the following is a specification, reference being had to the accompanying drawings, in which—

Figure 1 is a top view of my invention. Fig. 2 is a section on line 2 2 of Fig. 1. Fig. 10 3 is a section on line 3 3 of Fig. 1. Fig. 4 is a section on line 4 4 of Fig. 2.

My invention is a combined pistol and knife in which the pistol, made up of a barrel and a breech-piece, is fired by releasing a bolt or 15 striker contained within the breech-piece, to which piece the blades of the knife are secured, so that the pistol serves as a handle for the knife-blades.

In the drawings, A is the barrel of the pistol, and B B' the knife-blades. The barrel A is preferably made by boring out a block A' and swings on the pin a, so that it may be tipped up for the insertion or ejection of the cartridge a'. The knife-blades B B' are secured by the pin b to the breech-piece b², and the knife-blades swing on this pin b. The pins a b b' serve also to hold in place the side pieces D D' and the springs b³ b⁴ for the knife-blades, and the said side pieces D D' and the 20 springs b³ b⁴ hold the breech-piece b² and the barrel A in proper relation to each other. The breech-piece b² is bored out to receive the firing-bolt a², to which is fast the collar a³, which supports the striker a⁴, which slides 25 in the bore in the breech-piece b², the striker a⁴ being notched at a⁵ to receive the trigger-catch d.

The spring a⁶ is coiled around the firing-bolt a², one end of the bore in the breech-piece b² and the striker a⁴ serving as abutments for the spring. The trigger D² is mounted in a slot in the side of the breech-piece b² and carries at its lower end the catch d and is provided near its upper end with the notch d', which is engaged by shoulder d⁸ on safety-catch d². The trigger D² is held in place by the spring d⁶. The safety-catch d² is a lever fulcrumed at d⁵ and provided with the shoulder d⁸, which engages the notch d' in 45 the trigger D² and is held in engagement therewith by spring d⁷, so that before the trigger D² can be pushed down and the striker a⁴ re-

leased the catch d² must be swung forward on its fulcrum against the force of the spring d⁶.

The barrel A is held in place by the catch F, which moves endwise in a slot in the breech-piece b² and is held in engagement with a notch in the block A' by the spring d⁸. Mounted on the under side of the block A' is the rod H, which is held in place by screw-heads h h. 55 This rod is provided at one end with a shoulder h', which bears against the rim of the cartridge, and at the other end the rod H is curved to form handle h², so that when the barrel is swung on the pin a the handle h² 60 may be grasped, the rod H moved endwise, and the cartridge extracted.

Secured to the breech-piece b² between the blades B B' is the lever M, pivoted on the pin m³. The short arm of the lever M is provided 70 with finger-piece m and the long arm is provided with the shoulder m', which when the lever is in the position shown in the drawings is between the breech end of the block A' and the collar a³, so that if the safety-catch d² should be released the firing-bolt a² 75 could not reach the cartridge unless the shoulder m' should first be pressed down. The lever M is held in its normal position by the spring m².

To cock the pistol, the curved arm a⁷, fast to the firing-bolt a² is grasped and the firing-bolt a² is pulled out, carrying with it the striker a⁴, until the forward end of the striker a⁴ is engaged by the catch d on the trigger 85 D², after which the firing-bolt a² and the collar a³ may be pushed back into place, the pistol then being at full-cock, but being prevented from accidental discharge by the safety-catch d² and the shoulder m' on lever M. 90

To discharge the pistol, the breech-piece b² is grasped in the hand, the thumb resting against the safety-catch d² and the trigger D² and one of the fingers of the hand bearing 95 on the finger-piece m of the lever M. The thumb is pressed forward to disengage the safety-catch d², and at the same time lever M is swung on the pin m³ by the pressure of the finger and the trigger is pressed down, disengaging the catch d from the striker a⁴, which is thrown forward by the spring a⁶ and strikes against the collar a³, thus throwing the end of the firing-bolt a² against the rim of 100

the cartridge a' , thereby exploding the cartridge.

In my invention the pistol is adapted to use the principle of bolt action used heretofore in military rifles. The forward action of the bolt does not derange the aim as the downward blow of a hammer does, especially in these small weapons. By securing the knife-blades to the breech-piece of the pistol I gain 10 the advantages that the pistol may be fired with the knife-blades in their open position without danger of fouling or corroding the blades. Furthermore, this position of the knives does not interfere with the aim of the firer, and the weight of the knife-blades in 15 their open position balances the weapon and aids materially in obtaining accuracy of fire.

I am aware of Patent No. 49,784, dated September 5, 1865, and Patent No. 53,473, dated 20 March 27, 1866, both granted to A. J. Peavey,

and I disclaim all shown in them, for in my combined pistol and knife the pistol is adapted to be fired by the forward action of a bolt and the knife-blades are secured to the breech-piece of the pistol, and by this construction I obtain the advantages above referred to.

What I claim as my invention is—

The combined pistol and knife above described, made up of a block A', bored to form the barrel of the pistol; a breech-piece b^2 bored to receive the firing mechanism and slotted to receive the trigger and safety-catches, a firing-bolt a^2 ; and knife-blades, B B', secured to the breech-piece b^2 .

JOSEPH C. WHITE.
